WEFT REPLENISHING LOOM WITH REGULARLY MOVING TRANSFERRER

Filed July 16, 1928

UNITED STATES PATENT OFFICE

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT-REPLENISHING LOOM WITH REGULARLY-MOVING TRANSFERRER

Application filed July 16, 1928. Serial No. 293,022.

This invention relates to improvements in weft replenishing looms having regularly moving transerrer arms and it is the general object of the invention to provide means to prevent indication of weft at the time of transfer and also to release an untransferred bobbin.

In co-pending application Ser. No. 293,014 filed by King there is shown a device which is operative at the time of transfer to prevent indication of weft exhaustion. This device operates by a force communicated through the yielding bobbin support and as shown in that application the bobbin support is always in bobbin supporting position except when being moved by the incoming bobbin at the time of transfer. It occasionally happens that a bobbin will be slow in being released from one or another of the stacks of reserve bobbins and will not arrive under the transerrer arm but will be held by the latter to one side of the transfer position as the transerrer arm moves downwardly. The result of this faulty operation of the mechanism will be to permit the bobbin to move into transfer position during the upward or non-transferring stroke of the transerrer arm and be inserted into the active shuttle on the next stroke of the transerrer arm toward the shuttle. If the shuttles have shifted in the meantime the bobbin will be put into the wrong shuttle and a fault will occur in the pattern.

It is an important object of my present invention to combine with the King construction a simple mechanism for moving the bobbin support to bobbin releasing position so that not only will the repeated indication be prevented but an untransferred bobbin will be released, these joint results being accomplished by substantially the same cooperating devices.

In mechanisms of the type to which the present invention more particularly relates the transerrer arm has a non-transferring stroke away from the shuttle every alternate beat of the loom to effect rocking of a color slide which is an important part of the ordinary multicolor weft replenishing mechanism. It is another object of my invention to derive movement from this non-transferring

regularly recurring stroke of a transerrer arm to rock the giveaway or support for the bobbin so that the latter will be released before another transferring stroke of the transerrer arm can take place. This feature 55 of my invention may be used either with the construction shown in the aforesaid King application or independently of such a construction.

With these and other objects in view which 60 will appear as the description proceeds, my invention resides in the combination and arrangement of parts hereinafter described and set forth in the claims.

In the accompanying drawings wherein a 65 convenient embodiment of my invention is set forth,

Fig. 1 is a side elevation of a portion of a multicolor weft replenishing mechanism having my invention applied thereto and 70 showing the parts in the position they assume normally on non-indicating and non-transferring beats of the loom with the transerrer arm in its lowest position,

Fig. 2 is a view similar to Fig. 1 but with 75 the parts in the position they assume on transferring beats of the loom,

Fig. 3 is a view similar to Fig. 2 but with the transerrer arm moved to a higher position and with the bobbin support moved to 80 release an untransferred bobbin, and

Fig. 4 is a horizontal section on line 4—4 of Fig. 1.

Referring to Figs. 1, 2 and 3 I have indicated a loom frame 10 having a multicolor 85 weft replenishing mechanism 11 supported thereby. A transerrer arm 12 pivoted on a fixed stud 13 is given a reciprocating movement in a vertical plane by a rod 14 which is caused to move downwardly on detecting 90 beats of the loom and to move upwardly immediately after detecting by mechanism not shown. The transerrer arm 12 does not move immediately to its extreme upward position, this latter movement taking place at a later 95 time in the cycle of the loom when the active shuttle is on that side of the loom opposite the transerrer arm 12.

A weft detector, the lower end of which is indicated at 15, is supported by the trans- 100

ferrer arm and is moved into contact with the yarn W of the active shuttle S by mechanism not shown and forming no essential part of my present invention. A plunger 16 is slidably mounted on the transferrer arm and is normally held in non-indicating position so as to clear an indicating lever 17 as the trans-
5 ferrer arm moves upwardly on non-indicat-
ing detecting beats of the loom.

10 The indicating lever 17 is pivotally mounted on a stud 18 fixed to the magazine frame and said lever has a horizontal arm 19 which by means of a vertical rod 20 has operative connection with a color slide 21. The latter is movable longitudinally and angularly in bearings 22 formed as part of the magazine frame and the color slide is movable longitudinally by mechanism not shown but acting in timed relation with the shuttle boxes not shown. Said color slide will when at rest with respect to longitudinal motion be operatively related to one or another of the vertical slides 23 which control movements of the reserve bobbins B toward transfer position.
15

20 The indicating lever is provided with an upwardly and forwardly inclined face 24 de-
signed to cooperate with the plunger 16 when the latter is in indicating position. The transferrer arm is provided with a lug 25
25 which in its upward movement engages the stud 19' on the indicator lever 17 on each non-
detecting beat of the loom when the active shuttle is on the opposite side of the loom as previously described to rock the indicating
30 lever in a counter-clockwise direction as viewed in Fig. 1 to effect cooperation between the color slide 21 and any vertical slide 23 which may be in raised position and also co-
operatively positioned with respect to the
35 color slide.
40

45 In the operation of the mechanism thus far described the transferrer arm has a complete cycle of operations every two picks of the loom, moving downwardly to cause en-
gagement of the detector 15 with the weft of the active shuttle S every alternate beat of the loom when the active shuttle is under the magazine 11. When weft is present in suffi-
50 cient amount the transferrer arm will move upwardly without rocking the lever 17, but when weft is substantially exhausted the plunger 16 will be moved longitudinally to lie under the cam face 24 so that as the trans-
ferrer arm moves upwardly the indicator
55 lever will be rocked in a clockwise direction as viewed in Fig. 1 to raise the vertical slide 23 corresponding to the active shuttle. At a later time, namely, when the active shuttle is on the opposite side of the loom, the trans-
ferrer arm will complete its upward move-
60 ment to bring about engagement between the lug 25 and the indicator lever to cause the previously described counter-clockwise regu-
larly recurring oscillation of the indicating
65 lever.

The matter thus far described is substantially the same as that shown in prior patent to Ryon No. 1,372,316 to which reference may be had for a more complete disclosure of the construction and operation of the device. My present invention does not depend upon the particular manner in which the plunger 16 is moved into indicating relationship with the indicating lever and said plunger may if de-
70 sired be moved to indicating position by mechanism such as that shown in patent to Chevrette No. 1,604,258.
75

As previously stated, my present invention relates to means for releasing an untransferred bobbin and also to prevent initiation of transfer on transferring beats of the loom, these two results preferably being accom-
plished through the same cooperating mecha-
nism to effect simplicity of construction. In carrying my invention into effect I provide a yieldable bobbin support 40 which is secured to a stud 41 by a set screw 42. The stud is rotatable in the magazine frame and is sur-
80 rounded by a torsion spring 43 one end of which is connected to the magazine frame
85 and the other end of which is connected to a hub 44 of an upwardly extending arm 45. Said spring tends to turn the arm 45 in a counter-clockwise direction as viewed in Fig.
1, acting to hold said arm against a fixed stud 46 under normal conditions. By means of a set screw 47 the arm may be adjustably se-
cured to the stud 41.
90

95 The arm 45 cooperates with a pressure transmitting member 50 which is provided with a slot 51 through which extend a pair of bolts or screws 52. The latter are secured to the indicating lever 17 and by means of the slot 51 said member 50 is adjustable rela-
100 tively to the lever 17. The underside of the member 50 is provided with an opening 53 having two walls 54 and 55 which are located respectively in front of and behind the upper end of the arm 45 and are adapted for engage-
105 ment with the latter.
110

115 During the normal operation of the mecha-
nism the transferrer 12 will be moved to its extreme upward position once every other pick as previously described and when the lug 25 engages the indicating lever 17 to rock the same in a counter-clockwise direction the wall 55 will engage the upper end of the arm 45 to rock the latter in a clockwise direction around its axis, as shown in Fig. 3. The effect of this is to move the support 40 downwardly and also rearwardly so that the space be-
120 tween the forward end of the support 40 and the adjacent end of a bobbin guide 56 which is normally fixed with respect to the maga-
zine will be slightly more than the diameter of the bobbin. Should a bobbin remain on the supports 40 and 56 during the upward movement of the transferrer arm, therefore, said bobbin will be released to fall downward-
125 130

ly at a time when the transerrer arm is in raised position. In this way the placing of the wrong bobbin in the active shuttle is prevented. It is to be understood that this 5 movement of the support 40 preferably takes place on alternate picks of the loom.

The other feature of my invention, namely, the prevention of indication on transferring beats of the loom, is accomplished by co- 10 operation between the arm 45 and the wall 54. It is to be understood that immediately prior to transfer the bobbin which is to be inserted into the running shuttle will be held on the supports 40 and 56 and during the transfer- 15 ring operation the support 40 will yield against the action of spring 43, causing the arm 45 to move away from the stop 46 toward the wall 54. At this time the arm 45 will engage said wall 54 to rock the indicat- 20 ing lever 17 to the position shown in Fig. 2, where it will be seen that the lower end of said lever lies in the path of the indicating plunger 16. Should the latter be released by an improper action of the weft detector 25 on a transferring beat it will be held against moving into indicating relationship with the inclined face 24 of the indicating lever, so that the transerrer arm 12 may move upwardly after transfer without effecting rock- 30 ing movement of the indicating lever 17 in such a direction as would initiate a second replenishment.

It is to be understood of course that upon proper indications of weft exhaustion when 35 the plunger 16 may correctly move into indicating relationship with the face 24, the lever 17 will move in a clockwise direction and it is in order to permit this movement that I provide the space indicated at 60 between the forward portion of the arm 45 and the wall 54, see Fig. 1. The arm 45 is so proportioned 40 relatively to the support 40 that the motion of the upper end of said arm at the time of transfer will be sufficient not only to move across the space 60 but also to give the indicating lever 17 the movement necessary to 45 prevent a second indication, as shown in Fig. 2.

The regularly recurring contact between 50 face 55 and the arm 45 is accompanied by sufficient motion on the part of the indicating lever and the arm so that there will always be enough movement on the part of the support 40 to release the bobbin when the face 54 is correctly adjusted to produce proper co- 55 operation with the arm 45 to prevent repeated indication.

From the foregoing it will be seen that I 60 have provided a simple connection between the indicating lever and the yieldable bobbin support 40 effective to release an untransferred bobbin and also prevent indication of weft exhaustion on transferring beats of the loom. It will further be seen that the pres- 65 sure transmitting member 50 can be moved to

a variety of positions to effect a nicety of adjustment with respect to the face 54 while at the same time insuring sufficient motion on the part of the arm 45 to release an untransferred bobbin. It will furthermore be seen that at one point in a complete transferring cycle of the loom the arm 45 will be the actuated or driven member to effect releasing movement on the part of the support 40, and that at another part of the same cycle said arm 45 will become the actuator or driving member to move the indicating lever into a position where it will prevent initiation of a second transfer by the plunger 16.

Having thus described my invention it 80 will be seen that changes and modifications may be made therein by those skilled in the art without departing from the spirit and scope of the invention and I do not wish to be limited to the details herein disclosed, but 85 what I claim is:

1. In a weft replenishing loom provided with a transerrer arm having a regularly recurring transferring movement toward the shuttle at a predetermined time every alter- 90 nate beat of the loom and having a regularly recurring non-transferring movement away from the shuttle at some time other than the predetermined time, means to support a bobbin in transfer position, and means operated 95 by a force derived from the transerrer arm as the same has a non-transferring movement to act on the first named means to release an untransferred bobbin.

2. In a weft replenishing loom provided 100 with a transerrer arm having a regularly recurring transferring movement toward the shuttle at a predetermined time every alter- nate beat of the loom and having a regularly recurring non-transferring movement away 105 from the shuttle at some time other than the predetermined time, means operative by the transerrer arm as the same has its regular non-transferring movement to release an untransferred bobbin.

3. In a weft replenishing loom provided 110 with a transerrer arm having a regularly recurring transferring movement toward the shuttle at a predetermined time every alter- nate beat of the loom and having a regularly 115 recurring non-transferring movement away from the shuttle at some time other than the predetermined time, a bobbin support to hold a bobbin in transfer position, an element receiving a regular movement from the transerrer arm as the latter has its regular non-transferring movement, and means operatively connected to and moved by the element to move the bobbin support to bobbin releasing position.

4. In a weft replenishing loom having a transerrer arm which is given a transferring stroke toward the shuttle every alternate beat of the loom when the lay is in its forward position and a non-transferring stroke 130

in the opposite direction subsequently to the transferring stroke, means to support an untransferred bobbin under the transerrer as the latter moves on its non-transferring stroke, and mechanism actuated by the transerrer arm as the same moves on a non-transferring stroke to move said means to release an untransferred bobbin.

5. In a weft replenishing loom having a transerrer arm which is given a transferring stroke toward the shuttle every alternate beat of the loom when the lay is in its forward position and a non-transferring stroke in the opposite direction subsequently to the transferring stroke, a pivotally mounted bobbin support to hold a bobbin in transfer position, an indicating lever which is given a regular oscillation by the transerrer lever when the latter moves on its non-transferring strokes, and means moved by the indicating lever to move the bobbin support to release an untransferred bobbin as the transerrer moves on its non-transferring stroke.

25. 6. In a weft replenishing loom having a transerrer arm which is given a transferring stroke toward the shuttle every alternate beat of the loom when the lay is in its forward position and a non-transferring stroke in the opposite direction subsequently to the transferring stroke, means to release an untransferred bobbin, means to prevent initiation of weft replenishment on transferring beats of the loom, both of said means having a common member which is actuated during the transferring beat of the loom by a force derived from the transerrer arm to prevent initiation of weft replenishment and operative on the non-transferring stroke of the transerrer arm to release an untransferred bobbin.

40. 7. In a weft replenishing loom having a transerrer arm which is given a transferring stroke toward the shuttle every alternate beat of the loom when the lay is in its forward position and a non-transferring stroke in the opposite direction subsequently to the transferring stroke, means to release an untransferred bobbin, means independent of the transerrer arm to prevent initiation of weft replenishment on transferring beats of the loom, and mechanism operative on one stroke of the transerrer arm to operate one of said means and operative on the other stroke to operate the other means.

45. 8. In a weft replenishing loom having a shuttle and a transerrer arm movable toward the shuttle every alternate beat of the loom and movable away from the shuttle on the intervening beats, a movable bobbin support normally in bobbin retaining position, means moved by the support on transferring beats of the loom to prevent initiation of weft replenishment, and mechanism operating through said means to move the

support to bobbin releasing position when the transerrer arm moves away from the shuttle.

9. In a weft replenishing loom having a shuttle and a transerrer arm movable toward the shuttle every alternate beat of the loom and movable away from the shuttle on the intervening beats, a movable bobbin support normally in bobbin retaining position, an indicating lever movable to initiate weft replenishment, connections independent of the transerrer arm between the support and the lever to prevent initiation of weft replenishment on transferring beats of the loom, said indicating lever being moved by the transerrer arm as the latter moves on its stroke away from the shuttle to impart motion through said connections to the support to move the latter to bobbin releasing position.

10. In a weft replenishing loom having a shuttle and a transerrer arm movable toward the shuttle every alternate beat of the loom and movable away from the shuttle on the intervening beats, a movable bobbin support normally in bobbin retaining position, an indicating member movable at weft exhaustion to initiate replenishment, connections between the member and the support established at the time of transfer of a full bobbin into the active shuttle to prevent initiation of transfer by a force transmitted through the bobbin support, said transerrer arm giving the member a regular movement on the alternate beats when said transerrer arm moves away from the shuttle, said regular movement of the member being effective through the connections to move the bobbin support to bobbin releasing position.

11. In a weft replenishing loom having a shuttle and a transerrer arm movable toward the shuttle every alternate beat of the loom and movable away from the shuttle on the intervening beats, a movable bobbin support normally in bobbin retaining position, and indicating member movable at substantial weft exhaustion to initiate replenishment of weft, a pressure transmitting element secured to the member, a device moving with the bobbin support and adapted for cooperation with the element, said device on transferring beats of the loom engaging the element to move the member to prevent initiation of weft replenishment, the transerrer arm giving the number a regular movement on the alternate beats of the loom when said transerrer arm moves away from the shuttle to cause said element to move the device and support to move the latter to bobbin releasing position.

12. In a weft replenishing loom having a shuttle and a transerrer arm movable toward the shuttle every alternate beat of the loom and movable away from the shuttle on the intervening beats, a movable bobbin sup-

port normally in bobbin retaining position, and indicating member movable at substantial weft exhaustion to initiate replenishment of weft, a pressure transmitting element secured to the member, a device moving with the bobbin support and adapted for cooperation with the element, said device on transferring beats of the loom engaging the element to move the member to prevent initiation of weft replenishment, the transerrer arm giving the member a regular movement on the alternate beats of the loom when said transerrer arm moves away from the shuttle to cause said element to move the device and support to move the latter to bobbin releasing position, and means to hold said element in any one of a plurality of different positions on the member.

13. In a weft replenishing loom having a shuttle and a transerrer arm movable toward the shuttle every alternate beat of the loom and movable away from the shuttle on the intervening beats, a movable bobbin support normally in bobbin retaining position, an indicating member movable at substantial weft exhaustion to initiate replenishment of weft, a pressure transmitting element secured to the member, a device moving with the bobbin support and adapted for cooperation with the element, said device on transferring beats of the loom engaging the element to move the member to prevent initiation of weft replenishment, the transerrer arm giving the member a regular movement on the alternate beats of the loom when said transerrer arm moves away from the shuttle to cause said element to move the device and support to move the latter to bobbin releasing position, there being a lost motion connection between the device and the element, whereby the member may move to initiate replenishment without interfering with said device.

In testimony whereof I have hereunto affixed my signature.

45 WALTER H. WAKEFIELD.
